C. SAWYER

RAIL TIE AND RAIL FASTENING MEANS

Filed March 16, 1926

Patented Jan. 4, 1927.

1,613,295

UNITED STATES PATENT OFFICE.

CHARLES SAWYER, OF OCCOQUAN, VIRGINIA.

RAIL TIE AND RAIL-FASTENING MEANS.

Application filed March 16, 1926. Serial No. 95,081.

This invention relates to an improvement in a combined rail tie and rail fastening means.

It is an important object of the invention to provide an improved composite rail tie of metal and concrete, having embedded therein rail fastening means.

A further object is the provision of a tie so formed as to permit and expedite the proper tamping of the ballast thereabout.

Another object is the improved means for positively securing the rail upon the tie against displacement, whereby spikes and the like will be eliminated.

15 A still further object is the provision of a shield for the fastening means, carried by such fastening means, and adapted to protect the working parts from dirt, gravel, etc., incident to use.

20 Other important objects and advantages of the invention will be apparent during the course of the following description, reference being had to the accompanying drawings, in which like numerals are employed 25 to designate like parts throughout.

Referring to the drawings,

Fig. 1 is a plan view of a structure embodying the invention,

30 Fig. 2 is a side elevation thereof, parts in central vertical section,

Fig. 3 is an end view thereof,

Fig. 4 is a transverse vertical section, taken on line 4-4 of Fig. 2, and,

35 Fig. 5 is a perspective view of a rail securing member.

Referring specifically to the drawings, the numeral 10 designates parallel, horizontally extending side plates, of inverted L-shape, and 11 spaced centrally arranged parallel reinforcing plates of U-shape. The plates 10 and 11 are arranged in parallelism and held in spaced relation by a plurality of spacing sleeves 12, all of which are rigidly held by transversely extending bolts 13, passing through said sleeves. As clearly shown, the outer plates 10 are narrower than the plates 11.

40 The numeral 14 designates fixed co-acting clamping blocks, of a thickness equal to the space afforded between the plates 11, and rigidly held in position therebetween by bolts or rivets 15. The blocks 14 are flush with the bottom of the plates 11 and project thereabove a slight distance. The 45 blocks are provided with straight outer walls

16 and inner inclined walls 17, adapted to have contact with wedge-shaped clamping members 18. The members 14 and 18 are provided with angular tapered grooves 19, for the reception of a tapered locking pin 20, it being obvious that when the wedge 18 is in position, its groove 19 will register with the groove in the block 14.

The numeral 21 designates T-shaped anchor-blocks, adapted to co-act with substantially inverted L-shaped rail clamping members 22. The T-shaped blocks are of a thickness less than the blocks 14, and are rigidly fixed between the plates 11, by side filler plates 23 and bolts 24. The head of 70 the block 21 terminates flush with the top of the plates 11. The clamping members 22 are provided with a lower enlarged tail 25 and an enlarged angularly arranged head 26. The head 26 is adapted, when in position, to engage and clamp the base 27 of 75 the rail 28. The head is further notched as at 29, to properly engage over said base 27. As clearly illustrated in Fig. 2, the tails 25 of the clamps 22 engage beneath 80 the shoulders 21' of the blocks 21, for preventing vertical displacement of the clamps, while permitting a downward movement thereof when pressure is placed on the rails 28. The wedges 18 are adapted, when in 85 use, to engage both the blocks 14 and clamps 22, in a manner clearly illustrated in Fig. 2.

The heads 26 of the clamps are further provided with upstanding apertured lugs 30, adapted to be engaged by curved shields 90 31. The shields 31 are provided with rectangular openings for the reception of the lugs 30, and are retained thereon by pins 32. The shields 31 extend entirely across the width of the tie, and outwardly a distance sufficient to cover the blocks 14. The purpose of these shields, is to protect the working parts of the rail clamping elements against rocks, dirt etc., incident to use, and tamping the tie.

100 It is desirous to provide a cushioning means for the rail and to accomplish this, a body of cushioning material 33 has been provided and positioned between a pair of horizontally arranged plates 34, the lowermost plate resting upon the tops of the plates 10 and 11, while the upper plate receives and supports the base 27 of the rail. The plates 34 and cushion 33 are of a length sufficient to extend entirely across the tie trans- 110

versely and are notched as at 35 to permit the clamps 22 to properly engage the rail.

As clearly shown, the spaces between the plates 10 and 11, and the space between the plates 11, outwardly of the blocks 14, are filled with a plastic composition 36, such as concrete. The body of the concrete, beginning at the bottom of the plates 10, is rounded longitudinally, to permit proper tamping of the ballast. Suitable sockets 37 may be formed between the plates 11 during the molding of the ties, and bolts 38 extend across these sockets and have bearings in the plates 11. The purpose of these sockets and bolts is to provide a ready means of attaching hooks or other implements used in handling the tie. The plates 10 and 11 provide suitable reinforcing for the plastic body, and the plates 10 further provide means to prevent chipping or otherwise injuring the body of concrete 36 during handling. All fixed members, including the plates 10 and 11 and blocks 14 and 21, are rigidly bolted together prior to the pouring of the mass of concrete therebetween. In molding the tie, it is usually inverted, as all parts, excepting the blocks 14, are flush with the tops of the plates 10 and 11. This will enable the pouring and forming of the rounded portions of the concrete in an expeditious manner. Suitable curved molds would be employed in forming the sockets 37.

The operation of the device is as follows: It being assumed that the tie has been placed and properly tamped, and the detachable parts removed, the cushioning member is first placed in position and the rail rested thereon. The clamps are then inserted between the plates 11 so that their tails 25 will hook beneath the shoulders 21', and are then swung to a vertical position in engagement with the rail, the clamps entering the notches 35 of the cushioning member. The wedges 18 are then inserted between the clamps 22 and the fixed blocks 14 and are forced downwardly so that the grooves 19 will register. When in this position, the clamps will have been forced into rigid clamping engagement with the rails. The tapered pins 20 are then inserted, and a cotter pin or other fastening means is employed to prevent displacement thereof. The shields 31 are then positioned upon the lugs 30 and are held thereon by the pins 32. It will be obvious that the notching of the cushion elements, and the engagement of the clamps 22 therein, will avoid displacement of the cushions. The engagement of the tails 25 beneath the anchor 21 will permit proper functioning of the cushion, for the reason that the clamps may move downwardly, but cannot rise above the point of contact of the shoulders of the anchor and the tail 25.

It will be apparent from the foregoing, 65 than an extremely simple and efficient form

of rail tie and rail securing means has been provided. The tie construction is of exceptionally strong and simple construction. The metal employed therein is preferably of stock size, avoiding the added cost of special material. The use of the plates upon the sides is advantageous for the reason that the tie is protected against breakage in handling, as has been the case of former concrete ties. The rail securing means is such as to positively prevent displacement of the rail accidentally, and the parts are simple and quickly and easily assembled. The use of the cushion is a further protection to the tie against the attendant jarring in use. The use of the shield is also an added and valuable feature of the invention.

It is to be understood that the invention is not limited to the particular construction set forth but that it includes within its purview whatever changes may fairly come within either the terms or the spirit of the appended claims.

Having described my invention, what I claim as new and desire to secure by Letters Patent is:—

1. A railway tie comprising a body portion of concrete, reinforcing plates embedded therein, metal side plates bolted thereto, rail securing means rigidly supported by said tie, rail clamps engaging said securing means, means for forcing said clamps into engagement with the base of the rail and a shield carried by said clamps.

2. A railway tie comprising a body portion of concrete, parallel longitudinally extending reinforcing plates embedded therein, parallel side plates bolted to said body portion and lying in parallelism with said reinforcing plates, rail securing means rigidly supported between said reinforcing plates, a resilient rail chair supported upon said tie, rail clamps, means carried by said clamps for engaging said securing means whereby said clamps will be held against vertical movement when in the clamped position, wedge elements for engaging said clamps and said securing means, means carried by said clamps for engaging the base of the rail, lugs carried by said clamps at their upper ends and shield engaging said lugs, said shields of such size as to entirely cover said rail securing means.

3. A rail tie comprising a plurality of longitudinally arranged spaced parallel plates the upper edges of which are flush and the outermost plates formed narrower than the inner plates, spacing sleeves for holding said plates in spaced relation during the construction of the tie, bolts for rigidly holding said plates in position, the space between said plates adapted to receive a body of concrete, rail securing means rigidly supported between the innermost plates, said body of concrete having recesses

formed upon its upper surface adjacent its ends and bolts extending transversely of said recesses.

4. A rail tie of the character described comprising a body of concrete, spaced parallel longitudinally extending reinforcing plates of U-shape embedded therein, spaced outer longitudinally extending inverted L-shape plates bolted to the body of the tie, 10 said outer plates formed narrower than the inner plates for permitting the rounding of the body of concrete upon its lower longitudinal edges, said body of concrete provided with recesses upon its upper surface adjacent its ends, bolts supported by said inner plates and extending transversely of said recesses, anchor blocks rigidly supported between said inner plates, rail clamping members adapted to engage said blocks, 20 wedge blocks rigidly supported between said inner plates and spaced from said anchor blocks, wedges for engaging said wedge blocks and said clamping members, rail supporting plates supported upon the upper surface of said tie, resilient cushions supported between said plates, lugs carried by said clamping members, and curved shields supported upon said lugs.

5. A rail tie comprising a body portion of concrete having inner and outer spaced longitudinally extending reinforcing plates, the inner plates being embedded therein and the outer plates bolted thereto, wedge blocks supported between the inner plates and of such width as to be engaged by both of said inner plates, anchor blocks rigidly supported between said inner plates inwardly of said wedge blocks, said anchor blocks being of a width narrower than the wedge blocks, and rigidly supported between said plates by spacing plates, clamping elements adapted to engage upon opposite sides of said anchor blocks and to project above said tie for engagement with the base of the rail, wedges adapted to engage between said inner plates and have wedging contact with said wedge blocks and said clamping elements, whereby said clamping elements will be held against displacement with respect to said anchor blocks and said rail base, rail supporting plates supported upon said tie, cushioning material positioned between said plates, said plates and said cushioning material notched adjacent said clamping elements, for the reception of said clamping elements, apertured lugs carried

by said clamping elements at their upper ends, curved shield plates, having openings formed therein for the reception of said lugs, said shields extending transversely of 60 said tie and curved downwardly throughout its length, pins for retaining said shields in position, and pins for retaining said wedges in position.

6. A rail tie formed of a body of concrete 65 and having reinforcing plates embedded therein, said tie having openings formed therein adjacent its ends extending from top to bottom and of a width equal to the space between the said plates, anchor blocks 70 rigidly supported centrally of said openings, said anchor blocks formed of a T-shape, wedge blocks rigidly supported at each end of said openings and extending above the top of said tie, said anchor blocks having their upper ends flush with the upper surface of said tie, rail supporting plates supported upon the surface of said tie and above said anchor blocks, said plates extending transversely of said tie and terminating flush 75 with the outer edges thereof, cushioning material supported between said rail plates, rail clamps, said clamps having a hooked lower end adapted when in position to engage beneath the head of the anchor block, 80 said clamps provided with an enlarged angular head adapted to engage the base of a rail, said clamps notched out adjacent said head whereby said head will be enabled to engage over the base a greater distance, said 85 rail plates and said cushioning material notched out for the reception of the body of the clamps, whereby said clamps are adapted to closely engage said base, and further to prevent displacement of said plates and 90 said cushioning material, apertured lugs formed upon said heads, curved shields having openings formed therein for the reception of said lugs, wedges adapted to engage between said wedge blocks and said clamps, 95 100 said blocks and said wedges having angular grooves formed therein that are adapted to register when the wedges are in position, angular pins adapted to engage in said openings formed by said grooves, said shields of 105 a width sufficient to cover the wedge blocks, and curved throughout its length downwardly.

In testimony whereof I affix my signature.

CHARLES SAWYER.
